UNITED STATES PATENT OFFICE.

MAURICE R. SWOPE, OF ALTON, ILLINOIS.

PRIMING COMPOSITION AND METHOD OF PREPARING THE SAME.

1,073,941.

Specification of Letters Patent. **Patented Sept. 23, 1913**

No Drawing.

Application filed April 23, 1913. Serial No. 763,071.

To all whom it may concern:

Be it known that I, MAURICE R. SWOPE, a citizen of the United States, and a resident of Alton, in the county of Madison and State of Illinois, have invented a new and Improved Priming Composition and Method of Preparing the Same, of which the following is a full, clear, and exact description.

10 This invention relates to a new priming compound for use with explosive cartridges and the like. This new compound has been tested in various cartridges, with a variety of makes of smokeless powder, and has been 15 found to give a higher and less variable velocity to the projectile than the priming compounds hitherto employed. It possesses the further advantage over the latter that there is practically no erosion of the gun barrel 20 when using my primer made as hereinafter described. It has proved sufficiently sensitive to explode quickly in weak spring guns, and is less dangerous to handle than mercury fulminate. The ignition is quick and 25 the flame hot and penetrating.

The following is a description of the process by which I prepare the new priming compound: I first prepare a gelatinous mass compounded of gun cotton or pyroxylin 30 and amorphous phosphorus, in the following proportions: Gun cotton 80 parts; amorphous phosphorus 20 parts. As solvent in this operation I may use either acetone, or, in case so-called soluble cotton is employed, 35 I may use a mixture of ether and alcohol in the proportion of two parts to one part. After this mass has become thoroughly dry, I pulverize it and mix it with the following

ingredients in the proportions stated: Gun cotton-phosphorus compound 25 parts, potassium chlorate 37.5 parts, antimony sulfide 37.5 parts.

The resulting body is a priming compound possessing the advantages hereinbefore pointed out.

While the proportions indicated above have been found the most suitable for general purposes, I do not limit myself to these proportions, but may employ the ingredients stated in quantities varying within certain limits from those given.

Having thus described my invention, what I claim as new and desire to secure by Letters Patent is:

1. A process of producing a priming composition, which consists in preparing a mixture of gun cotton and amorphous phosphorus, allowing the said mass to dry, powdering the same, and mixing therewith potassium chlorate and antimony sulfide.

2. A priming composition containing gun cotton and amorphous phosphorus, potassium chlorate and antimony sulfide.

3. A priming composition containing the following ingredients in substantially the proportions stated: Gun cotton 20 parts; amorphous phosphorus 5 parts; potassium chlorate 37.5 parts; antimony sulfide 37.5 parts.

In testimony whereof I have signed my name to this specification in the presence of two subscribing witnesses.

MAURICE R. SWOPE.

Witnesses:

J. H. CHALK,

WILL D. THORN.
